UNITED STATES PATENT OFFICE.

HENRY J. HANZLIK, OF LYNN, MASSACHUSETTS, ASSIGNOR TO GENERAL ELECTRIC COMPANY, A CORPORATION OF NEW YORK.

TURBINE VALVE-GEAR.

1,006,654.

Specification of Letters Patent. Patented Oct. 24, 1911.

Application filed March 22, 1909. Serial No. 484,883.

To all whom it may concern:

Be it known that I, HENRY J. HANZLIK, a citizen of the United States, residing at Lynn, county of Essex, State of Massachusetts, have invented certain new and useful Improvements in Turbine Valve-Gear, of which the following is a specification.

This invention relates to elastic fluid turbines, and its object is to improve the valve gear, whereby live steam or other motive fluid can be fed at will to other than the first stage of the turbine.

The construction hereinafter set forth is designed especially for turbines which are intended to be run either condensing or non-condensing according to the circumstances under which they must be operated. Non-condensing operation tends to decrease the output of the machine, so it becomes necessary to provide for correcting this, even at the expense of efficiency.

My invention aims to accomplish this by providing a separate set of overload nozzles for the second stage, and for other intermediate stages if desired, such overload nozzles being supplied with steam independently of the regular stage nozzles through pipes controlled by hand valves. When the engine is run condensing, these valves are kept closed, and the steam passes from stage to stage in the usual manner. But when it becomes necessary to run non-condensing, then the hand valves are opened, one or more, as may be necessary, and live steam or other motive fluid is fed directly to the special overload nozzles of the second stage, and to other stages if desired.

In the accompanying drawings, Figure 1 is a side elevation of a portion of a horizontal steam turbine, partly in section, embodying my improvements; Fig. 2 is an end view of the steam chest and a portion of the second stage nozzles; Fig. 3 is a top plan view of the same.

The usual casing 1 incloses the shaft 2 and the wheels 3 mounted on said shaft and carrying the buckets 4. In the drawing; there are two wheels per stage, the buckets co-operating with the stationary intermediates 5. The nozzles 6 which deliver the steam to the first stage wheels, are fed through the passage 7 to which the steam is admitted by the valves 8 which are controlled by the governor mechanism 9 in the usual manner. A bypass leads from the steam

passage 7 to the overload nozzles, comprising a passage 10 running to a chamber 11, the entrance to which is controlled by the valve 12, which has a spindle 13 passing through a stuffing box 14 and provided with a hand wheel 15 outside of the auxiliary steam chest 16. The auxiliary chest is cast with or secured to the main steam chest 17. From the chamber a pipe 18 conveys the steam to a compartment 19 from which one or more special nozzles 20 direct it upon the buckets of the first wheel in the second stage of the turbine. The special nozzles are not those to which the steam is led from the first stage of the machine, which are shown at 21 in Fig. 2. In Fig. 1 the nozzles 6 and 20 appear to be in the same longitudinal plane, but as a matter of fact they are in different planes; the showing in the drawing having been adopted for the sake of simplicity of illustration.

Two hand valves and pipes 18 are shown in the drawings, but this number is merely illustrative and may be varied at will. Each hand valve controls its own independent chamber 11, pipe 18 and compartment 19, and there may be one or more of the special nozzles 20 connected with each of the compartments. The bowls of the special nozzles form a part of said compartments which are cored out in a thick internal flange 22 cast integral with the casing. In this flange also are formed the passageways which lead from the first stage to the regular second stage nozzles.

The speed governor is contained in a casting 25 and is driven by the low speed shaft 26 through suitable gearing from the main shaft 2. The nozzle valves may be actuated in a variety of ways. In the present illustration of my invention they are actuated by a connecting rod 27, lever 28 and shaft 29. The action of said parts on the valve stem is controlled by the speed governor through the rod 30, arm 31, lever 32, connecting rod 33 and arm 34.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is—

1. In a multistage turbine, admission and regular stage nozzles, an auxiliary stage nozzle, a conduit supplying high pressure fluid to the auxiliary nozzle and separating the inlet of the auxiliary nozzle from the inlet of said regular nozzles, a valve that is common to an admission nozzle and the conduit, and a governor for controlling the valve.
2. In a multistage turbine, admission and regular stage nozzles, an auxiliary stage nozzle, a conduit supplying high pressure fluid to the auxiliary nozzle and separating the inlet of the auxiliary nozzle from the inlet of said regular nozzles, a valve that is common to an admission nozzle and the conduit, a governor for controlling the valve, and a hand valve for controlling the passage of motive fluid through the conduit independently of the governor valve.
3. In a multistage elastic fluid turbine having admission nozzles and regular stage nozzles, a steam chest receiving motive fluid from a suitable source, a bypass around the first stage, a hand-operated valve controlling said by-pass, a governor controlled valve that regulates the admission of steam from the steam chest to the admission nozzles and the bypass, one or more special nozzles supplied with steam from said bypass, and means separating the inlets of the special nozzles from the inlets of the regular stage nozzles.
4. In a multistage elastic fluid turbine having admission and regular stage nozzles, the combination with a plurality of gover-

nor-controlled valves, of one or more bypasses leading from the steam passages below said valves, a hand-operated valve in each bypass, one or more special nozzles taking steam from each bypass and directing it against the buckets of wheels in an intermediate stage, and means separating the inlets of the special nozzles from the inlets of the regular nozzles.

5. In a multistage elastic fluid turbine having admission nozzles and regular stage nozzles, auxiliary stage nozzles, a steam chest receiving motive fluid from a suitable source, conduits for conveying motive fluid from the chest so that it can flow in parallel to the admission and auxiliary nozzles, the conduit or conduits leading to the auxiliary nozzles separating the inlets of said nozzles from the inlets of the regular stage nozzles, and means for controlling the delivery of motive fluid to the nozzles.

6. In a multistage elastic fluid turbine, the combination with the main steam chest, of an auxiliary chest divided into chambers, governor valves in said main steam chest, hand-operated valves controlling the admission of steam from below the governor valves to said chambers, pipes leading from said chambers, and special nozzles for an intermediate stage of the turbine connected with the delivery ends of said pipes.

In witness whereof, I have hereunto set my hand this 19th day of March, 1909.

HENRY J. HANZLIK.
